UNITED STATES PATENT OFFICE

AUGUST RAPP, OF PULLMAN, ASSIGNOR TO GEORGE M. PULLMAN, OF CHICAGO, ILLINOIS.

DRAW-HOOK FOR STREET-CARS.

SPECIFICATION forming part of Letters Patent No. 351,793, dated November 2, 1886.

Application filed February 10, 1886. Serial No. 191,475. (No model.)

To all whom it may concern:

Be it known that I, AUGUST RAPP, a citizen of the United States, residing at the village of Pullman, in the county of Cook and State of Illinois, have invented a new and useful Improvement in Draw-Hooks and Springs therefor, for which I desire to obtain patents in the United States, of which the following is a specification.

10 It has been usual heretofore to place the draw-bars and the draft-hooks underneath the street-cars, and to cause the draft-strain to come directly upon the spring. This construction has the double disadvantage of throwing the points of attachment to the car too low and of necessitating a direct pull upon the spring, the latter feature causing, in practice, considerable inequality in the draft-pull upon the car.

15 20 My invention has for its object the devising of means for giving the draft-hook a higher position and also effecting an indirect action of the spring upon the draft-strain. To this end I propose to dispense entirely with the draw-bar, using instead thereof a lever pivoted to the nose-piece of the platform and carrying at its upper end the draft-hook, which is thus suitably elevated, and bearing at its lower end against a head-block moving in 25 30 guideways pivoted to the bottom of the car, against a spring.

My invention further consists in means for preventing the escape of the clevis from the draft-hook, which can be operated by the driver without reaching over the dash-board.

35 My invention further consists of certain details of construction, hereinafter fully described and pointed out in the claims.

In the drawings hereto annexed and forming a part of this specification, Figure 1 represents a front elevation of the nose-piece and dash-board of a street-car to which my inventions have been applied. Fig. 2 is a side view, partly in a section, of the same. Fig. 3 is a bottom view giving a section of the spring head-blocks and guard-pieces on line 3 of Fig. 2.

The two castings C, of shape shown in Figs. 1 and 2, are attached by bolts K to the nose-piece

50 A at a suitable distance on each side, respectively, of the center thereof, and carry a pivotal

bolt, H, upon which is hung the vertical lever D, provided at its upper end with a draft-hook, and having at its lower end, on its inner side, a rounded face, I, which bears upon the head-block G of the spring F. The lever D is made 55 of the shape shown, so that when under no strain its lower end is pressed out by the spring F and the inner edge of its upper part rests against the dash-board C, and when strain is applied to the draft-hook it is free to take 6c the position shown in the dotted lines in Fig. 2, compressing the spring F against its rear head-block L. The head-blocks G and L are curved above and below, as shown partially in dotted outline in Fig. 1, and have lateral 65 extensions S and Q, Fig. 1, which fit in grooves formed in the guide-pieces E E, and are also attached by bolts K to the nose-piece. The head-blocks have inwardly-extending circular lugs R R for retaining the spiral spring F in 7c its position.

It will of course be understood that my invention is not limited to the particular form of spring herein shown, or the particular form of mounting therefor, as an unlimited variety 75 of spring-bearings for the lower end of the draft-lever might be very readily devised. Neither do I confine myself to the particular position of the draft-lever shown, the essence 8c of my invention lying in the use of the lever intermediate between the draft-hook and the draft-spring.

The device which I have invented for preventing the escape of the clevis from the draft-hooks consists of a clip, O, attached to a pivotal bolt, P, and having a pin, T, passing through the said bolt to prevent the slipping of the clip on the bolt, the said bolt P passing through the dash-board and having at its inner end a handle, N, similarly attached to it 85 by a pin.

It is obvious that when the handle N is turned from the inside of the dash-board the clip O will follow it, and thus can be readily thrown by the driver to and from its closing 95 position with reference to the draft-hook.

I claim—

1. In a street-car, the combination of a pivoted lever provided with a draft-hook at one end, a spring mounted between sliding head-

blocks, and a guideway for said head-blocks, the rear end of said lever resting upon one of the head-blocks and tending to compress the spring under the draft-strain.

5 2. The combination of lever D, provided with a draft-hook, pivot H therefor, attached to the front of the car, guide-pieces E E, bolted to the bottom, and spring F and head-blocks LGtherefor, moving between said guide-pieces, so said spring receiving and equalizing the effect upon the car of the draft-strain, substantially as described and shown.

10 3. The combination, with a draft-hook, of a

catch for closing the entrance to the same on the outside of the dash-board of the car, a handle inside of the dash-board, and a bolt passing through the dash-board and rigidly connected to both the catch and the handle, whereby the catch can be moved to and from the inside of the dash-board, substantially as described and shown.

AUGUST RAPP.
